(57) **CLAIM**

The ornamental design for an insect eliminating device, as shown and described.

DESCRIPTION

FIG. 1 is a front view of an insect eliminating device showing our new design;

FIG. 2 is a rear view thereof;

FIG. 3 is a top perspective view thereof;

FIG. 4 is a bottom perspective view thereof;

FIG. 5 is a top view thereof;

FIG. 6 is a bottom view thereof;

FIG. 7 is a side view thereof; and,

FIG. 8 is an opposite side view thereof.

The broken lines illustrate environmental structure and form no part of the claimed design.
